Primary Examiner — Calvin E Vansant*Assistant Examiner* — Eidiol Ghigliotti Torres(74) *Attorney, Agent, or Firm* — Taft Stettinius & Hollister LLP; Stephen F. Rost(57) **CLAIM**

The ornamental design for a bypass elbow, as shown and described.

DESCRIPTION

FIG. 1 is a perspective view of a first embodiment of a bypass elbow shown according to the present design;

FIG. 2 is a front end view thereof;

FIG. 3 is a rear end view thereof;

FIG. 4 is a top view thereof;

FIG. 5 is a bottom view thereof;

FIG. 6 is a left side elevational view thereof; and,

FIG. 7 is a right side elevational view thereof.

The broken line representations in the figures show unclaimed environment or boundaries. The broken line representations thus form no part of the claimed design as filed.

1 Claim, 5 Drawing Sheets(56)
